REPEATER MECHANISM FOR WEFT
REPLENISHING LOOMSWalter H. Wakefield, Worcester, Mass., assignor
to Crompton & Knowles Loom Works, Worcester,
Mass., a corporation of Massachusetts

Application February 5, 1944, Serial No. 521,206

14 Claims. (Cl. 139—232)

This invention relates to improvements in multi-stack weft replenishing mechanism and it is the general object of the invention to provide means by which bobbins may be drawn in rotation from a plurality of stacks of similar bobbins.

Fancy weft replenishing looms generally employ a magazine having plural stacks of reserve bobbins which are released for transfer by a selector registerable with the stacks one at a time. In the usual loom there is a stack for each shuttle and the selector moves in timed relation with the shifting of the shuttle boxes which place the shuttles in action. In the weaving of certain fabrics, however, one type of weft is likely to be used more frequently than another type, and in such cases it is desirable to use two or more stacks for replenishment of the more frequently used weft. As an example, curtains have clip spots woven with a coarse loose weft similar to roving and a ground weave woven with much finer yarn.

It is an important object of my present invention to provide mechanism by which the selector acting through the bobbin releasers for the several stacks causes rotation of a shaft or the like which in turn moves a stop for the selector to different positions to cause the selector to register with the several stacks in a given sequence. The shaft preferably has step by step movements all in the same direction and is provided with a crank connected to the stop and operative to raise and lower the latter so that its steps may move into and out of the path of the selector.

In certain types of fabrics two types of decorative coarse weft are used, one being used more frequently than the other, and there is also a fine weft for the ground weave of the fabric. In such instances it is desirable to distribute the reserve bobbins in the magazine in the approximate proportion in which the wefts are used, assigning two stacks for the more frequently used coarse weft, a third stack for the less frequently used coarse weft, and a fourth stack for the finer ground weft. It is another object of my present invention to provide a form of controller for the selector stop so constructed that by a slight adjustment of the aforesaid crank on the shaft the mechanism can be converted from a form in which three stacks supply weft of the same kind to a form in which only two stacks supply the same kind of weft.

In this second or modified form of the invention three shuttle boxes are used which can

shift through two equal one-space shifts. It is a further object of the invention to provide connections between the shuttle boxes and selector so constructed that the latter will have a two space shift relatively to the releasers for one of the one-space shifts of the shuttle boxes, and will have only a one space shift relatively to the releasers for the second one-space shift of the shuttle boxes.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a multi-stack weft replenishing mechanism as seen from the center of the loom, having the preferred form of my invention applied thereto.

Fig. 2 is an enlarged vertical section on line 2—2 of Fig. 1, showing the operating pawl for the shaft in its extreme high and low positions.

Fig. 3 is a view similar to Fig. 2 but showing the pawl in the two positions which it assumes at the beginning and at the end of a turning movement of the shaft.

Figs. 4, 5 and 6 are diagrammatic views showing the preferred form of control exercised by the shaft over the stop when the mechanism is set for drawing bobbins in rotation from three stacks.

Figs. 7, 8, 9 and 10 are diagrammatic views showing the modified form of control wherein the mechanism is set to draw bobbins from two stacks.

Figs. 11 and 12 are enlarged detailed vertical sections on lines 11—11 and 12—12, respectively, of Fig. 1, the parts in Fig. 11 being in the position shown in Fig. 3.

Fig. 13 is a diagrammatic view showing the connections between two shuttle boxes and the stack selector used in the preferred form of the invention.

Fig. 14 is similar to Fig. 13 but showing the connections between three shuttle boxes and the stack selector as used in the modified form of the invention, and

Fig. 15 is a detail view of the lever used in the connections of the modified form of the invention, as seen from the rear of the loom.

Referring particularly to Fig. 1, the loom frame 10 supports a multi-stack magazine M having four stacks of bobbins 11, 12, 13 and 14 provided with vertically reciprocating bobbin releasers 15, 16, 17 and 18, respectively. Each releaser oper-

ates a cradle 19 connected to the lower end thereof and rockable in opposite directions to effect bobbin delivery from the associated stack. Each releaser has top and bottom lugs 20 and 21, respectively, for cooperation with front and back selector fingers 22 and 23, respectively, forming part of a selector designated generally at 24. The latter includes in its construction a rod or shaft 25 slidably mounted for horizontal movement with respect to the magazine in front and back bearings 26 and 27, respectively.

The selector shaft 25 has secured to the rear end thereof a collar 30 provided with a groove 31 which receives the upper end of a positioning lever 32 pivoted at 33 to the magazine frame. A spring 34 connected to lever 32 and having its upper end anchored as at 35 with respect to the magazine frame tends normally to move lever 32 in a clockwise direction to move the selector 24 forwardly, or to the right, see Fig. 1.

The selector 24 includes in its construction a web 40 cooperating with an actuating lever 41 connected to the upper end of a vertically movable rod 42. The lower end of the latter is connected to a floating lever 43 pivoted intermediate its ends on a block 44 carried by the upper end of a vertically reciprocable rod 45.

The upper part of the magazine frame has front and back bearings 46 and 47, respectively, in which rocks a shaft 48 the front end of which has secured thereto an arm 49 connected to a depending rod 50 attached to a transfer latch or dog 51. The latter is normally below a bunter 52 on the lay L and is connected to a transfer arm 53 pivoted as at 54 on the stand 55 of the magazine. Shaft 48 has secured thereto a second arm 60 connected by rod 61 to a shuttle position detector designated generally at 62 and pivoted as at 63 on a fixed part of the magazine. A depending arm 64 of the shuttle position detector carries the usual head not shown normally in forward position but movable rearwardly at the time of a transfer to determine whether the shuttle is properly boxed to receive a reserve bobbin. Shaft 48 has secured thereto a casting 70 having a shelf or bar 71 for cooperation with dogs 72 on the upper ends of the bobbin releasers 15 to 18.

The matter thus far described is of common construction in multi-stack weft replenishing mechanisms and operates in the usual manner. The bobbin releasers are normally down and bar 71 is raised to the full line position shown in Fig. 2 and the cradles are empty. The rod 45 moves downwardly when the lay is on front center and a shuttle is in shuttle box B at the magazine end of the lay L. If at this time the detector D indicates weft sufficiency a pin 66 connected to the detector is moved to non-controlling position with respect to lever 43 and the latter has an idle motion, permitting rod 42 to remain unmoved so that the selector 24 is not given a rocking movement. If, however, the detector indicates exhaustion of weft in the box B, the pin 66 remains in its normal position to interrupt downward movement of the floating lever 43 and the latter thereupon depresses rod 42 to cause rocking of the selector 24 in a clockwise direction as viewed in Fig. 2 to raise its fingers 22 and 23. The bobbin releaser registered with the selector is thereupon raised and its dog 72 moves outwardly under action of spring 75 on the releaser to overhang the bar 71, see full lines, Fig. 2. Replenishment of the depleted shuttle is thus

initiated and the shuttle is picked to the opposite end of the loom.

When the shuttle returns rod 45 is given an upward movement, this movement occurring regularly at two-pick intervals and coming at that part of the loom cycle at or about the time the box shift at the opposite end is completed. Lever 43 is thereupon raised to lift rod 42 and cause a reverse rocking of the selector 24 to depress its fingers. The previously raised bobbin releaser is thus depressed, moving down to its normal position to rock the associated cradle for bobbin delivery. At the same time the associated dog 72 rocks the bar 71 to the dotted line position shown in Fig. 2, raising rod 61 to move the shuttle position detector 62 rearwardly, and lowering rod 50 to lift the transfer latch or dog 51 into the path of the lay carried bunter 52. As the lay approaches front center position the transfer arm 53 is depressed to move the released bobbin under it into the shuttle in box B. During the latter part of the forward movement of the lay which effects transfer the shuttle position detector 62 is rocked in the counter-clockwise direction as viewed in Fig. 1 to exert a downward pull on rod 61 to restore the top shaft 48 to its normal position. The magazine is thus reset and is ready for another transfer operation.

The two extreme angular positions of the shelf 30 shown in Fig. 2 are determined by a yielding lock mechanism of well-known construction designated generally at K. This lock includes an arm 77 secured to shaft 48, a second arm 78 movable about a fixed pivot 79, and a spring 80 operating on a block 80'. In the usual construction arm 77 is close to the front bearing 46 of shaft 48, but in the present instance and for reasons which will appear hereinafter I prefer to secure the arm 77 to shaft 48 a slight distance in front of the bearing 46.

Except as noted the matter thus far may be substantially similar to that shown in prior Patents Nos. 1,030,748 and 1,633,648.

In carrying my present invention into effect I provide each dog 72 with an upwardly extending hook or pawl 81 which is controlled by the associated spring 75. A stand 82 is secured to the upper part of the magazine frame and has front and back bearings 83 and 84, respectively. A shaft 85 is rotatably mounted in these bearings and has a collar 86 secured to the rear end thereof behind bearing 84 to limit motion of the shaft to the right as viewed in Fig. 1, and also has a crank arm 87 secured to the front end thereof in front of bearing 83 which limits rearward movement of the shaft, or movement to the left as viewed in Fig. 1. The longitudinal position of the shaft is therefore determined and does not change during shaft rotation.

Shaft 85 carries three ratchet wheels 90, 91 and 92, respectively, each having a hub 93 provided with a set screw 94 to secure the associated ratchet to the shaft. Each ratchet preferably has six teeth and is positioned for cooperation with the corresponding pawl 81. The crank arm 87 has a set screw 95 which permits the crank arm to be set with respect to the shaft 85 in two selected positions relatively to the teeth of the ratchet wheels 90, 91 and 92 for purposes which will appear hereinafter. Crank 87 also carries a pin 96 which cooperates with either of two stop mechanisms to be described for the selector 24.

When the magazine is to have its preferred setting so that the three stacks 11, 12 and 13

have similar bobbins to replenish one shuttle, each of the three ratchet wheels will be in alignment with its corresponding pawl 81 and a form of stop having three steps will be used. This stop, designated at S3, comprises a rod 100 having a slot 101 in the upper end thereof to receive pin 96 of the crank. The lower end of rod 100 is provided with a stop head 102 having stop surfaces 103, 104 and 105 corresponding to stacks 11, 12 and 13, respectively. Rod 100, as viewed in Fig. 1, extends down from pin 96 behind shaft 48 and between front bearing 46 and lock arm 77 secured to shaft 48.

In order to hold the shaft yieldingly in any of its six positions I provide a yielding lock 115 shown in Fig. 12 and comprising a wheel 116 secured to shaft 85 at 117 and having six notches 118 to receive a spring lock 119 secured as at 120 to the plate 82. The locking device 115 serves to hold shaft 85 and pin 96 in any position to which they are moved by the pawls 81, but yields to permit the shaft to move from one position to the next position thereof.

When the preferred form of the invention is to be used the loom will have a gang G2 of shuttle boxes at the left end thereof, as shown in Fig. 13. This gang has upper and lower boxes 125 and 126, respectively, for shuttles SA and SB, respectively. By well-known mechanism the gang G2 is shifted so that either of the shuttle boxes can be in active picking position with respect to the race plate 127 on lay L. A connector 130 extends from gang G2 around guide sheaves 131 and upwardly to the rear arm 132 of lever 32. The ratio between the two arms of lever 32 is such that when the gang G2 shifts upwardly from the position shown in Fig. 13 to place shuttle box 126 in active position, the selector 24 will be moved from its extreme front to its extreme rear position, that is, from registry with releaser 15 to registry with releaser 18. Thus, it will be seen that in the preferred form of the invention the loom operates with two shuttles, one of which SA is provided with a weft which is consumed more rapidly in the weaving operation than the weft of shuttle SB.

In the operation of the preferred form of the invention the magazine will be set to deliver bobbins of the same kind from stacks 11, 12, and 13, while the second type of weft less frequently used or consumed at a slower rate will be in stack 14. The pattern being woven will be such that shuttle SB will be active at comparatively frequent intervals, and shuttle SA will not be continuously active for a long enough period to consume a full bobbin. The selector 24 will therefore be moved to its rear position by shifting gang G2 at least as often as replenishment of shuttle SA is needed, and preferably more often.

When shuttle SA is depleted, detector D will cause the selector to rock in a counter-clockwise direction as viewed in Fig. 2 to raise whichever of the releasers 15, 16 or 17 is registered with it. It may be assumed that stop S3 is in high position so that surface 103 of head 102 registers the selector with releaser 15 and that the latter is raised preparatory to the first replenishment of shuttle SA. As this releaser is raised it moves from the dotted to the full line position shown in Fig. 2 and during the latter part of its upward motion dog 72 will be moved over bar 71 by spring 75 and at the same time pawl 81 will be moved to operative position over adjacent teeth of ratchet wheel 90. The shuttle SA is then picked to the opposite side of the loom and after time

has been allowed for a shift of the gang G2, but assuming that no shift will occur at this point of the operation, selector 24 is rocked in a clockwise direction as viewed in Fig. 2 to depress the previously raised releaser 15.

During descent of releaser 15 dog 72 will rock shaft 48 in a clockwise direction as viewed in Fig. 2 in usual manner to set the magazine for transfer as already described, and pawl 81 will move down from the full line position in Fig. 2 above one of the teeth of ratchet wheel 90 to the full line position shown in Fig. 3, where it engages the aforesaid ratchet tooth. Further descent of the releaser 15 will move the pawl 81 to the dotted line position shown in Fig. 3, thereby giving the shaft a 1/6th rotation, but at this time lug 140 of dog 72 will engage shoulder 141 of the magazine frame to rock the pawl 81 and dog 72 in a counter-clockwise direction, see Fig. 2, thereby resetting the dog and moving the pawl 81 away from the ratchet 90 back to the normal dotted line position shown in Fig. 2 as releaser 15 completes its down motion.

Arm 87 is set so that during the six angular steps needed to complete a rotation of shaft 85 the pin 96 will be at three different distances from shaft 25. It may be assumed for instance that at the beginning of the operation just described arm 87 is in the dotted line position shown in Fig. 5 so that the stop head 102 is in high position with the surface 103 in alignment with the selector to register the latter with the front releaser 15. The 1/6th rotation mentioned turns the shaft 85 in a counter-clockwise direction to the full line position shown in Fig. 5 which leaves the pin 96 at its previous distance from the shaft 25, and the selector remains registered with stack 11.

When shuttle SA is again depleted releaser 15 will again be raised to draw a second bobbin from front stack 11, but this time as releaser 15 descends its pawl 81 will rock shaft 85 and cause arm 87 to move to the full line position shown in Fig. 4 which places pin 96 nearer shaft 25 and can therefore permit the stop head 102 to fall. When selector 24 again moves rearwardly incident to activity of shuttle SB, the stop 102 will fall and the top of slot 101 and pin 96 will cooperate to place surface 104 in the path of the selector and register the latter with releaser 16.

The third replenishment of shuttle SA will cause movement of arm 87 to the full line position shown in Fig. 6 and head 102 will have a still further downward movement to place pin 96 in its nearest stationary position to shaft 25 and locate stop surface 105 in the path of the selector to register the latter with releaser 17. During the fourth replenishment of shuttle SA a bobbin will be drawn from the third stack 13, and arm 87 will be moved across to the dotted line position shown in Fig. 6 where pin 96 is at its previous distance from shaft 25 and the stop surface 105 will remain in controlling position with respect to the selector to keep the latter registered with the third releaser 17.

On the fifth replenishment of shuttle SA arm 87 will move to the dotted line position shown in Fig. 4 to lift the stop head so that its surface 104 will register the selector with releaser 16. On the last or sixth replenishment of shuttle SA in the cycle arm 87 will be moved back to the dotted position shown in Fig. 5 the effect of which is to place stop surface 103 in the path of the selector and again register the latter with the front releaser 15.

Thus it is seen that for six transfers involving shuttle SA pin 96 is given six different positions at three different distances from shaft 25, thereby registering the selector twice with each of the stacks 11, 12 and 13. Bobbins are therefore uniformly drawn from the front three stacks in a rotation which permits utilization of practically all the bobbins in these front stacks for replenishment of shuttle SA. If shuttle SB should need replenishment at any time the selector will be in its rearmost position and releaser 18 will rise and fall in usual manner, but since this releaser cannot turn shaft 85 replenishment of shuttle S2 will not interrupt the sequence in which bobbins are drawn from the front three stacks.

In the modified form of the invention I contemplate the adaptation of the structure thus far described to a loom operating with three shuttles one of which carries weft which is consumed more rapidly than the weft of either of the other two shuttles. Such a condition is frequently found in curtain fabrics where one decorative stripe predominates and is woven by one shuttle and where a less frequently used decorative weft is woven by another shuttle, while the ground weft is laid by a third shuttle. Under these conditions it is desirable to replenish the more rapidly consumed weft from the front pair of stacks 11 and 12 and replenish the other two shuttles from the rear stacks 13 and 14.

Fig. 14 diagrammatically shows a loom of the type having three shuttles used in the modified form of the invention. A gang G3 of shuttle boxes has top, intermediate and bottom shuttle boxes 150, 151 and 152, respectively, occupied by shuttles SC, SD and SE, respectively. Each shuttle becomes active when its corresponding shuttle box is in alignment with the race plate 127 on the lay L.

Since the gang G3 passes through two equal one step shifts when shifting to its three positions, the connections to the selector 24 must be modified to effect correct registry of the selector with the stacks corresponding to the shuttles as they become active. When shuttle SC is active the selector can be registered either with releaser 15 or 16, but when shuttle SD is active the selector must register with releaser 17. The shift of the shuttle box up one space from the full line position shown in Fig. 14 to place shuttle SD in action therefore requires a two stack shift of the selector from registry with the front releaser 15 to registry with the third releaser 17. The second one space shift of gang G3 to place shuttle SE in action would produce a second two-stack shift of the selector to a position behind releaser 18 if the ordinary type of connection were used between the shuttle boxes and the selector. In this latter box shift it is desirable to give the selector a one-stack shift so that it can register with releaser 18.

In order to accomplish the desired result I introduce a lever 155, see Figs. 14 and 15, in the connection between the gang G3 and the selector so constructed that equal angular movements thereof derived from the gang G3 will produce an amount of shift in the selector when gang G3 has its first rising movement equal to twice the shift of the selector when gang G3 has its second upward movement. This lever is indicated in Fig. 15 which is a view from the rear of the loom, whereas the same lever is shown in Fig. 14 as seen from the front of the loom. Lever 155 is pivoted at 156 to a stand 157 on the loom arch 158 and has a downwardly extending arm 159 pivoted to

10 a rod 160 which is connected to some part moving with the shuttle boxes, such as the box chain 161 customarily employed in worsted looms and connected to the box lifter rod 162 of gang G3. Rod 160 has three longitudinal positions depending upon the position of gang G3, and moves the arm 159 to the positions shown in full lines, heavy dotted lines and light dotted lines in Figs. 14 and 15.

15 Lever 155 has a second upwardly extending arm 165 attached to a rod 166 attached to a flexible connector 167 extending around sheaves 168 and attached to a lever 169. A spring 170 operatively connected to the selector 24 tends to move the latter forwardly. The angle between arms 159 and 165 is such that when the lever 155 moves from the full line position to the heavy dotted line position in Fig. 15 the rod 166 will be moved longitudinally to the right a distance 20 corresponding to a two stack shift of the selector, and when the lever moves from the heavy dotted line position to the light dotted line position in Fig. 15 the rod 166 has a further movement to the right, which, however, corresponds to a one stack shift only of the selector. When arm 165 is vertical as shown in full lines in Fig. 15, arm 159 will diverge from a vertical line at an angle of 41°, 24'. It is found that this is the correct angle for producing the desired movements of rod 161, although an angle of 40° will give sufficiently close results.

25 When shuttle box 150 is in active position the selector will be able to register either with releaser 15 or 16, and when shuttle box 151 is active the selector is moved to register with releaser 17, while movement of shuttle box 152 to active position effects registry of the selector with releaser 18.

30 In the modified form of the invention ratchet wheel 92 is moved out of register with the pawl 81 of releaser 17 to some such position as that indicated in dotted lines in Fig. 1. Vertical reciprocation of the releaser 17 will therefore be inoperative to cause angular movement of the shaft 85. The ratchets 90 and 91, however, are maintained in registry with their respective hooks 81. Crank arm 87 is also changed with respect to shaft 85, being moved through an angle of 30° from the position occupied by it in the preferred form of the invention, and a second form of stop S2, shown more particularly in Figs. 7 to 10, replaces stop S3. When thus altered the loom will replenish shuttle SC from either of the stacks 11 or 12, replenish shuttle SD from stack 13, and replenish shuttle SE from stack 14, as will be apparent from the following description.

35 The change in the setting of arm 87 results in placing pin 96 at four different distances from shaft 25 during a six step cycle of shaft 85 corresponding to one complete rotation of it. In Fig. 7 pin 96 is shown at its lowest position where it is nearest shaft 25 and the upper part of surface 112 on head 110 of stop S2 will serve to stop the selector in register with releaser 16. When a replenishing operation of shuttle SC occurs arm 85 will be moved to the dotted line position shown in Fig. 8, thus placing pin 96 at its second distance from shaft 25 and raising the head 110 so that the lower part of surface 112 will keep the selector 24 in register with releaser 16. At the next transfer involving shuttle SC arm 87 will move to place pin 96 at its third distance from shaft 25, see the dotted lines of Fig. 10, and the 40 upper part of stop surface 111 will be operative

to register the selector 24 with releaser 15 of the front stack 11. At the next replenishment of shuttle SC pin 96 will move to its fourth or greatest distance from shaft 25, see Fig. 9, thus raising the stop head 110 so that the bottom of surface 111 will keep selector 24 in register with the front releaser.

During the following transfer pin 96 will move to its third distance from shaft 25 shown in full lines in Fig. 10, thereby again placing the upper part of surface 111 in the path of the selector to maintain the latter in registry with the front releaser. At the next replenishment of shuttle SC the pin 96 moves to its second distance from shaft 25 shown in full lines, Fig. 8, to locate the lower part of surface 112 in position to register the selector with the second releaser 16.

In this modified form it will be seen that when pin 96 is at its third and fourth distances from shaft 25, surface 111 registers the selector with the front releaser 15, and when pin 96 is at its nearest and second distances from shaft 25, stop surface 112 will cause registry of the selector with the second releaser 16.

Shuttles SD and SE can be replenished from their stacks 13 and 14, respectively, without interrupting the described sequence set forth in Figs. 7 to 10, due to the fact that releasers 17 and 18 are unable to turn shaft 85.

In the preferred form of the invention frequent shifting of gang G2 is relied upon to move selector 24 rearwardly so that the stop S3 may fall into the path of the selector before the latter returns forwardly incident to activity of shuttle SA. In the modified form activity of either shuttle SD or SE will cause rearward movement of the selector to permit stop S2 to fall to its different positions. So far as movement of the stops to their new positions are concerned the gangs G2 and G3 can be considered as displacing means which move the selector rearwardly to permit falling of the stops into correct position.

From the foregoing it will be seen that I have provided simple means by which down motion of the releasers turns a shaft which locates a stop in different positions in the path of the selector. It will also be seen that the arm 87 can be fixed to the shaft 85 in two different positions with respect to the ratchet wheels, so that the pin 96 can assume positions at three different distances from shaft 25 when three stacks of the magazine replenish the same kind of weft, or assume positions at four different distances from shaft 25 when two stacks supply the same kind of weft, two of the four positions corresponding to registry of the selector with the front stack 11 and the other two corresponding to registry with the second stack 12. It will further be seen that the rods forming parts of the stops S2 and S3 pass downwardly between the bearing 46 and stop arm 77, thereby permitting the use of a rod which has only a slight amount of offset in order to clear the parts between crank arm 87 and the selector. It will also be seen that when it is decided to use the magazine in the more usual settings wherein it supplies bobbins of four different types, all of the ratchets can be moved to inoperative position on shaft 85 so that descent of the pawls 81 will not change the position of the stop, and the latter can be held in its highest position to register the selector with the front stack, thereby permitting registry of the selector with any of the other three stacks. Furthermore, lever 155 provides a convenient means for

converting two equal movements of the gang G3 into unequal movements of the selector one of which is twice the other.

Having thus described my invention it will be seen that changes and modifications may be made therein by those skilled in the art without departing from the spirit and scope of the invention and I do not wish to be limited to the details herein disclosed, but what I claim is:

10. 1. In a weft replenishing loom having a given plural number of stacks of reserve bobbins each provided with a bobbin releaser actuated by a selector movable into registry with the releasers one at a time, the loom having displacing means to move the selector away from registry with said releasers and also having return means to move the selector back into registry with one or another of said releasers, a stop for the selector having as many steps as there are stacks of reserve bobbins and capable of assuming as many different positions with respect to the selector as there are stacks, each position corresponding to registry of the selector with a different releaser, a crank rotatably mounted on the loom, means operative during a succession of weft replenishing operations of the loom to give the crank successive step by step angular movements to move the crank to different working positions, and connections between the crank and the stop cooperating with said displacing and return means to effect movement of the stop to the different positions thereof as the crank rotates and moves to the different working positions thereof, thereby causing the stop to effect register of the selector with the different releasers in rotation.
20. 2. In a weft replenishing loom having three stacks of reserve bobbins each provided with a bobbin releaser actuated by a selector movable into registry with the releasers one at a time, the loom having displacing means to move the selector away from registry with the releasers and also having return means to move the selector back into registry with one or another of said releasers, a stop for the selector having three steps and capable of assuming three different positions to locate the steps one at a time in stopping position with respect to the selector to effect registry of the latter with the different releasers, a crank rotatable on the loom, and means operative during a succession of replenishing operations of the loom to give the crank successive partial rotations and cause the crank in cooperation with said displacing and return means to effect movement of the stop to the three different positions thereof with respect to the selector, thereby causing said selector to register with the releasers in rotation.
30. 3. In a weft replenishing loom having two stacks of reserve bobbins each provided with a bobbin releaser actuated by a selector movable into registry with the releasers one at a time, the loom having displacing means to move the selector away from registry with the releasers and also having return means to move the selector back into registry with one or the other of said releasers, a stop for the selector having two steps and movable to locate the steps one at a time in stopping position with respect to the selector to effect registry of the latter with one or the other of said releasers, a crank rotatable on the loom, and means operative during a succession of replenishing operations of the loom to give the crank successive partial rotations and cause the crank in cooperation with said displacing and return means to effect movements of the stop to

locate the steps, one at a time, in stopping position with respect to the selector.

4. In a weft replenishing loom having a given plural number of stacks of reserve bobbins each provided with a bobbin releaser actuated by a selector movable into registry with said releasers, one at a time, the loom having displacing means to move the selector away from registry with said releasers and also having return means to move the selector back into registry with one or another of said releasers, a stop for the selector having as many steps as there are stacks of bobbins and capable of assuming as many positions with respect to the selector as there are stacks, each position corresponding to registry of the selector with a different releaser, a crank rotatably mounted on the loom, means operated by the releasers as the latter are operated in succession by the selector to move the crank to different working positions, and connections between the crank and the stop cooperating with said displacing and return means to effect movement of the stop to the different positions thereof as the crank rotates, thereby causing the stop to register the selector with the different releasers in rotation.

5. In a weft replenishing loom having a given plural number of stacks of similar reserve bobbins each provided with a bobbin releaser actuated by a selector movable into registry with said releasers, one at a time, the loom having displacing means to move the selector away from registry with said releasers and also having return means to move the selector back into registry with one or another of said releasers, a stop for the selector having a number of steps equal to said given plural number of stacks and capable of assuming a number of positions equal to said given plural number of stacks, each position corresponding to registry of the selector with a different releaser, a crank rotatably mounted on the loom, means operated by the releasers as the latter are actuated in rotation by the selector to move the crank to a number of different working positions which is a multiple of said given number of stacks of similar reserve bobbins, and connections between the crank and the stop cooperating with said displacing and return means and operative during a rotation of said crank to effect movement of the stop to such positions as will cause the selector to register with said releasers.

6. In a weft replenishing loom having three stacks of reserve bobbins each provided with a bobbin releaser actuated by a selector movable into register with the releasers one at a time, the loom having displacing means to move the selector away from registry with said releasers and also having return means to move the selector back into register with one or another of said releasers, a stepped stop for the selector capable of assuming three positions each corresponding to registry of the selector with a different releaser, a shaft rotatably mounted on the loom, a crank on said shaft operatively connected to said stop, and means operated by said releasers when the latter are actuated by said selector one by one to give the shaft successive partial rotations and cause the crank in cooperation with said displacing and return means to effect movement of said stop to the different positions thereof.

7. In a weft replenishing loom having three stacks of reserve bobbins each provided with a bobbin releaser actuated by a selector movable into register with the releasers one at a time, the loom having displacing means to move the selector away from registry with said releasers and also having return means to move the selector back into register with one or another of said releasers, a stop for the selector having two stops and capable of assuming two positions each corresponding to registry of the selector with a different one of said releasers, a crank

lecter away from registry with said releasers and also having return means to move the selector back into register with one or another of said releasers, a stepped stop for the selector capable of assuming three positions each corresponding to registry of the selector with a different releaser, a shaft rotatably mounted on the loom, three ratchets on said shaft, one ratchet for each releaser, a crank on said shaft operatively connected to said stop, the releasers when actuated in succession by the selector cooperating with their respective ratchets to turn the shaft step by step, said crank during the rotation of the shaft cooperating with said displacing and return means and operative due to the different angular positions thereof to move said stop to the different positions thereof.

8. In a weft replenishing loom having three stacks of reserve bobbins each provided with a bobbin releaser actuated by a selector movable into register with the releasers one at a time, the loom having displacing means to move the selector away from registry with said releasers and also having return means to move the selector back into register with one or another of said releasers, a stepped stop for the selector capable of assuming three positions each corresponding to registry of the selector with a different releaser, a shaft rotatably mounted on the loom, three ratchets secured to said shaft, one ratchet for each of said releasers, a pawl on each releaser to cooperate with the corresponding ratchet, a crank secured to said shaft, said releasers when actuated in succession by said selector acting through their respective pawls and the corresponding ratchets to give said shaft successive angular movements, and the crank operatively connected to the stop and cooperating with said displacing and return means and operative due to the angular position thereof to effect movement of said stop to the different positions thereof.

9. In a weft replenishing loom having three stacks of reserve bobbins each provided with a bobbin releaser actuated by a selector movable into register with the releasers one at a time, the loom having displacing means to move the selector away from registry with said releasers and also having return means to move the selector back into register with one or another of said releasers, a stepped stop for the selector capable of assuming three positions each corresponding to registry of the selector with a different releaser, a shaft rotatably mounted on the loom, a crank secured to the shaft, means operated by the releasers as the latter are actuated in succession by the selector to move the crank to three working positions at different distances from the selector, and connections between the crank and the stop and cooperating with said displacing and return means to effect movement of the stop to the three different positions thereof as the crank moves to the three different working positions thereof.

10. In a weft replenishing loom having two stacks of reserve bobbins each provided with a bobbin releaser operated by a selector movable into register with the releasers one at a time, the loom having displacing means to move the selector away from registry with said releasers and also having return means to move the selector back into register with one or the other of said releasers, a stop for the selector having two stops and capable of assuming two positions each corresponding to registry of the selector with a different one of said releasers, a crank

rotatably mounted on the loom and operatively connected to said stop, and means operated by each releaser when actuated by the selector to give the shaft a partial rotation, the crank when having successive partial rotations active in cooperation with said displacing and return means to effect movement of said stop to the different positions thereof and cause the selector to register with said releasers.

11. In a weft replenishing loom having two stacks of reserve bobbins each provided with a bobbin releaser actuated by a selector movable into register with the releasers one at a time, the loom having displacing means to move the selector away from registry with said releasers and also having return means to move the selector back into register with one or the other of said releasers, a two stepped stop for the selector capable of assuming two positions each corresponding to registry of the selector with a different one of said releasers, a crank rotatably mounted on the loom, means operated by the releasers as the latter are actuated in succession by the selector to move the crank to two working ranges of movement at different distances from the selector, and connections between the crank and the stop cooperating with the displacing and return means to effect movement of one step of the stop into position to cause the selector to register with one of the releasers when the crank is in one of said ranges of movement and effect movement of the other step of the stop into position to cause the selector to register with the other releaser when the crank is in the other range of movement thereof.

12. In a weft replenishing loom having two stacks of reserve bobbins each provided with a bobbin releaser actuated by a selector movable into register with the releasers one at a time, the loom having displacing means to move the selector away from registry with either of said releasers and having also return means to move the selector back into register with one or the other of said releasers, a stop for the selector having two steps and capable of assuming four different positions with respect to the selector, two of said positions corresponding to location of one step in stopping position relatively to the

selector and the other two positions corresponding to location of the other step in stopping position relatively to the selector, a crank rotatably mounted on the loom, means operated by the releasers as the latter are actuated successively by the selector to move the crank to four different working positions at four different distances from the selector, two of said working positions corresponding to said two positions and the other two positions corresponding to said other two positions, the crank during a rotation thereof cooperating with said displacing and return means to effect movement of the stop to said first two positions thereof and thereafter effect movement of the stop to the other two positions thereof.

13. In a loom having three shuttle boxes which shift through two equal one-space shifts and having a bobbin releaser selector movable through three equal one-space shifts, and connections between the shuttle boxes and selector including a lever having one arm operatively connected to the shuttle boxes and a second arm angularly disposed with respect to the first arm and operatively connected to said selector, said lever operative due to the angular relation of said arms to effect a movement of the selector through two of said three space shifts thereof when the shuttle boxes have the first of the two-space shifts thereof and said lever effecting movement of the selector through the third of the three shifts thereof when the shuttle boxes have the second one-space shift thereof.

14. In a weft replenishing loom having shifting shuttle boxes and a selector movable into register with four bobbin releasers, one at a time, a part moving in timed relation with the shuttle boxes and a second part connected to said selector, and a lever having an arm connected to one of said parts and a second arm connected to the other of said parts, said arms being so related that two successive equal movements in the same direction of the arm connected to the first named part will cause two successive movements of said other part one movement of which is twice as large as the other movement thereof.

WALTER H. WAKEFIELD.
